Inventor.

T. T. Greenwood

UNITED STATES PATENT OFFICE.

TALMA T. GREENWOOD, OF TEMPLETON, MASSACHUSETTS, ASSIGNOR, BY MESNE ASSIGNMENTS, TO CONDIT ELECTRICAL MANUFACTURING COMPANY, A CORPORATION OF MASSACHUSETTS.

RETARDATION DEVICE.

Application filed May 5, 1920. Serial No. 379,158.

To all whom it may concern:

Be it known that I, TALMA T. GREENWOOD, a citizen of the United States, residing at

Templeton, in the county of Worcester and State of Massachusetts, have invented an Improvement in Retardation Devices, of which the following is a specification.

This invention relates to retardation devices adapted to control the opening of an electric circuit by an electric switch and has especial reference to the type of device having a cylinder adapted to contain a fluid with an electrically actuated piston operable therein.

The object of the invention is to provide an improved retardation device and one having means whereby the retarding effect is a minimum at the start of its operation and increases as the actuating effect is increased.

Fig. 1 is a sectional elevation of a retardation device embodying my invention in its normal or unactuated condition,

Fig. 2 is a sectional elevation of the retarding device in an actuated condition,

Figs. 3 and 4 are sectional views for modifications of the invention,

Fig. 5 is a section along lines 3—3 of Fig. 1.

As here shown, the device is immersed in the oil contained in the oil receptacle 10 secured to and depending from the solenoid enclosing casing 11.

In that embodiment of the invention illustrated in Fig. 1, the retardation device includes the cylinder 12 secured to said casing and depending therefrom. A piston 13 is slidably disposed within said cylinder and is substantially oil tight therein and is connected by the rod 14 to the solenoid core 14' or other piston actuating means. Said cylinder is formed with the end wall 15 having the perforations 16 therethrough preferably adjacent its periphery. The lower end of the cylinder is externally screwed threaded to receive the clamping ring 17 having the inwardly extending flange 18. A flexible diaphragm 19 of thin material having the central perforation 20 therein is secured to the end of the cylinder by said ring 17 and a spacing ring 21 interposed between the end wall of the cylinder and the diaphragm serves to hold the diaphragm above but closely spaced from the end wall

whereby to provide an oil passage 22 connecting the aperture 20, and the perforations 16 in the end wall.

It is to be noted that the diaphragm is adapted to be flexible and to yield under a fluid pressure difference on opposite sides of it, and the perforations 20 and 16 are offset so that the oil must travel along the space 22 between the diaphragm and the end wall. Said diaphragm and end wall of the cylinder constitute valve members controlling the flow of fluid into the cylinder.

When the piston begins to be moved upwardly within its cylinder a pressure difference is set up between the cylinder and the oil in the oil receptacle, thereby causing a flow of oil into the cylinder. This pressure difference acts on said flexible disc or diaphragm 19 and the disc yields or is deflected toward the end wall of the cylinder, thereby restricting the passage 22 and diminishing the rate of flow of oil into the cylinder, and the deflection of the diaphragm and consequent restriction of the fluid flow may be proportional to the actuating force applied to the piston whereby the time period of operation of the device may be the same regardless of the strength of the actuating force. When the actuating means is a solenoid, the initial actuating force may be small, and the retarding effect is correspondingly low whereby the core will be positively moved within the solenoid; and when the core has been moved therein a short distance, the actuating force is increased and the retarding effect is correspondingly and automatically increased.

Preferably I so arrange the thickness of the spacing ring that the space 22 is about equal to one fourth the diameter of the perforation 20 but this obviously may be altered to accomplish specific performances.

In the modification shown in Fig. 3 the cylinder is open ended and a valve stem 25 is extended through the perforation 20 in the flexible disc 19 and is supported by the arm 26 carried by the clamping ring. The yielding of the flexible diaphragm 19 under a pressure difference acting thereon serves to throttle the opening 20 thereby to restrict the flow of oil therethrough.

In the modification shown in Fig. 4 the yielding diaphragm is replaced by the yielding piston 30 slidably arranged in the bore

31 of the cylinder and normally pressed outward by the spring 32. The end wall of said piston has the valve opening 33 therein in which the needle valve 34 carried by the 5 end wall of the cylinder is extended. A pressure difference acting on said piston serves to move it upward against the action of said spring 32 thereby to throttle the valve opening.

10 I claim:—

1. A retardation device comprising a cylinder, a piston operable therein, and a valve governing the fluid communication with said cylinder, said valve normally biased toward 15 open position and constructed and arranged to be actuated by an unbalanced fluid pressure acting on it to reduce the flow of fluid through it as a function of the unbalanced fluid pressure.

20 2. In a retardation device, a stationary valve member, a flexible diaphragm having a fluid aperture therethrough movable toward and away from said valve member thereby to govern the flow of fluid through 25 the aperture and normally biased away from said valve member, and means to flex said diaphragm comprising means to set up a fluid pressure difference on opposite sides of it.

30 3. In a retardation device a relatively stationary valve member, a relatively movable valve member having an aperture therethrough movable toward and away from said stationary member to govern the flow of fluid 35 through the aperture and means to move said movable valve member comprising means to set up a fluid pressure difference on opposite sides of it.

4. In a retardation device, a cylinder having a flat end wall with fluid apertures 40 therethrough adjacent the side-wall, a diaphragm having an aperture in it out of alignment with said other apertures closely spaced from said end wall flexible toward and away therefrom to govern the flow of 45 fluid through its aperture, and means to flex said diaphragm including a piston operable within said cylinder.

5. In a retarding device, a cylinder having a flat end-wall with fluid apertures therethrough adjacent its side-wall, a flexible diaphragm having a fluid aperture throughout of alignment with said fluid apertures, means to secure said diaphragm closely spaced above the end-wall of said cylinder, 55 said diaphragm capable of being flexed toward and away from said end-wall thereby to vary the flow of fluid through the aperture therein, and means to set up a pressure difference between opposite sides of said diaphragm to flex it including a piston operable within said cylinder.

6. In a retardation device, a cylinder having an end-wall with fluid apertures therethrough adjacent its side-wall, a piston operable therein, a flexible diaphragm having a central fluid aperture therethrough over the end wall of said cylinder, and means securing said diaphragm to the cylinder closely spaced above its end-wall admitting 65 of free fluid communication with the outer face of said diaphragm.

In testimony whereof, I have signed my name to this specification.

TALMA T. GREENWOOD.
